UNITED STATES PATENT OFFICE.

ROSS M. G. PHILLIPS, OF WEST HAVEN, CONNECTICUT, ASSIGNOR TO THE SENTINEL AUTOMATIC GAS APPLIANCE CO., OF NEW HAVEN, CONNECTICUT, A CORPORATION.

GAS-BURNING FLAT-IRON HEATER.

1,109,937.

Specification of Letters Patent. Patented Sept. 8, 1914.

Application filed March 27, 1914. Serial No. 827,531.

To all whom it may concern:

Be it known that I, Ross M. G. PHILLIPS, a citizen of the United States, residing at West Haven, in the county of New Haven and State of Connecticut, have invented a new and useful Improvement in Gas-Burning Flat-Iron Heaters; and I do hereby declare the following, when taken in connection with the accompanying drawings and the characters of reference marked thereon, to be a full, clear, and exact description of the same, and which said drawings constitute part of this application, and represent, in—

15 Figure 1 a plan view of a gas-burning flat-iron heater constructed in accordance with my invention, showing two burner-units. Fig. 2 a view thereof in vertical longitudinal section on the line *a*—*b* of Fig. 20 1. Fig. 3 a view thereof in transverse section on the line *c*—*d* of Fig. 1, showing a valve-operating member in its elevated or gas cut-out position by full lines, and in its depressed or gas-feeding position by broken 25 lines.

My invention relates to an improvement in that class of gas-burning flat-iron heaters in which the gas-valves are in part operated by the weight of the irons, the object being 30 to produce at a low cost for manufacture, a simple and convenient device of the character described.

With these ends in view, my invention consists in a gas-burning flat-iron heater 35 having certain details of construction and combinations of parts as will be hereinafter described and pointed out in the claim.

For the purpose of illustrating my invention, I have shown and described a 40 heater having two burner-units, but a heater having one burner-unit or an indefinite number of burner-units may be constructed in accordance with my present invention. As herein shown, I employ two skeleton 45 burner-frames 2 and 3 arranged side by side and supported at their ends upon the front and rear side bars of an oblong heater-frame 4 having legs 5 at its corners. As shown the left-hand burner-frame 2 is provided with an integral grid-iron like grill 35, which overhangs the left hand end of the heater-frame 4 and which is furnished for the temporary storage of a reserve iron. Beneath the respective burner-frames 2 and 50 3 I locate corresponding burners 6 and 7

having burner-ports 8 arranged along their edges in series. Each burner 6 is formed at its forward end with an assembling-stud 9 adapting it to be supported in a flange 10 depending from the forward end of the 60 burner-frame under which it is located. Each burner is provided at its rear end with an upwardly extending suspension-flange 11 terminating in a positioning-finger 12 entering a slot 13 in a horizontal flange 14 at the 65 rear end of its burner-frame. However, the particular construction of the burner-frame and burners may be varied. The said burners are respectively provided at their rear ends with integral conical mixing-chambers 70 15 receiving valves 16 and 17 united by elbows 18 connected by nipples 19 with a T 20 to which gas is brought through a supply-pipe 21 containing an ordinary key which is not shown. The valve-plugs (not shown) 75 within the valves 16 and 17 are normally maintained in closed positions by springs 22 which may be located within the valves if desired, as shown in my co-pending application filed February 21st, 1914, Serial No. 80 820,151. For the rotation of the said plugs, the same are provided with crank-like valve-stems 23 entering slots 24 in the rear ends 85 of long valve-actuating levers 25 which rock upon screw-studs 26 entered into threaded counterbores in the ends of alined hubs 27 cast integral with the burners and located between the same and the mixing-chambers 15 thereof. The forward ends of the respective levers 25, pass under the lateral 90 arms 28 (Fig. 1) of cradle-like valve-operating members each formed from a single piece of heavy wire and each comprising two upstanding, inclined flat-iron arms 29, united at their rear ends by a bow or loop 95 30, the forward ends of the said arms being bent inward toward each other to form pintles 31, by which the said members are pivotally mounted in the forward ends of the burner-frames 2 and 3. The said members are normally maintained in elevated 100 positions above the plane of the burner-frames by means of the springs 22 aforesaid, and as indicated by full lines in Figs. 2 and 3. The valves 16 and 17 are provided with 105 pilot-light couplings 33 from which small pilot-light pipes 34 lead forward alongside of the burner ports 8 of the respective burners 6 and 7.

Normally gas is excluded from the burners 110

6 and 7 by means of the normally closed valves 16 and 17, while the pilot-lights remain lighted. When a flat-iron is placed over either burner, the valve-operating member thereof will be depressed to the level of its plane and act through its appropriate valve-actuating lever to open the appropriate valve. The valve-operating members may be operated by flat-irons placed over the 10 burners lengthwise therewith, or cross-wise thereof. The said burner-frames are adapted in length to accommodate two irons placed side by side over it cross-wise, and the arms 29 of the valve-operating members 15 are long enough to be engaged and held down by either iron if either one is removed. My improved heater may therefore be used when it is provided with two burner units for concurrently heating from one to four 20 irons. The addition of more burner units would correspondingly increase its capacity. As shown the levers 25 are projected in front of the heater-frame 4 to enable them to be manually operated by the ironer for shutting 25 off the gas and so extinguishing the flame before she removes a heated iron.

I claim:—

In a gas-burning flat-iron heater, the combination with a horizontally arranged grill, of a pair of burners located side by side below the said grill, a pair of valve-operating members located below the said grill but having parts normally extending above the same, a pair of normally closed valves connected with the respective burners at the 30 rear ends thereof, and a pair of valve-actuating levers located below the said grill between the said burners and connecting the respective valve-operating members and valves for the opening of the latter upon 35 the depression of the said members by the appropriate placing of flat-irons upon the grill, the forward ends of the said levers being extended into position for their independent manual operation. 45

In testimony whereof, I have signed this specification in the presence of two subscribing witnesses.

ROSS M. G. PHILLIPS.
